UNITED STATES PATENT OFFICE.

LEOPOLD VAN ROY, OF BRUSSELS, BELGIUM.

DETACHABLE HEEL FOR FOOTWEAR.

Application filed August 9, 1924. Serial No. 731,226.

To all whom it may concern:

Be it known that I, LEOPOLD VAN ROY, a citizen of the Kingdom of Belgium, and resident of Brussels, Belgium, have invented 5 certain new and useful Improvements in or Relating to Detachable Heels for Footwear; and I do hereby declare the following to be a full, clear, and exact description of the invention, such as will enable others skilled 10 in the art to which it appertains to make and use the same, reference being had to the accompanying drawings, and to letters or figures of reference marked therein, which form a part of this specification.

15 This invention relates to improvements in detachable heels for footwear, made of rubber or other resilient material and cut or moulded so as to have preferably a concave-convex shape before being fixed to the heel 20 of the footwear, with the object of securing a contact at all points with the base of the shoe heel when placed in position.

The invention relates more particularly to 25 means for securing and automatically locking a rubber heel to an ordinary heel, the securing means being of the "bayonet joint" type.

In devices of this type as hitherto suggested the ordinary heel had grooves with 30 which hooks or ribs carried by the rubber heel were adapted to engage by the rotation of the two elements the one relatively to the other, these being afterwards separable by rotation in the reverse direction.

35 These devices have however the disadvantage that the connection of the elements is not sufficiently assured, so that, after a short period of use, the rubber heel is likely to be displaced laterally during walking, from the heel of the footwear. Moreover, with these 40 methods of attachment it is necessary to provide a special apparatus to prevent the relative angular displacements of the rubber heel after it has been fixed in position.

45 The present invention obviates these defects by the use of a fixing device having large contact surfaces, and which at the same time automatically locks the rubber heel after it has been placed in position.

50 With this end in view the invention consists in a device in which one of the two members (the rubber heel or footwear heel) carries two projections in the form of circular segments, of approximately 90° and 55 having a transverse section of dovetail form, the said projections being adapted when the

rubber heel is placed in position to engage with grooves having lateral cylindrical faces formed in the other element (footwear heel or rubber heel) and subsequently after the 60 rotation of one member relatively to the other, to engage with grooves which are a little deeper than the previous ones and have a section corresponding to that of the projections. 65

It is only after a rotation of the rubber heel around the said pivot that the dovetailed projections engage with the corresponding recesses of the other member, due to the resilient nature of the substance of 70 which one of the elements is formed.

Another object of the present invention is to prevent all angular displacements of the rubber heel relatively to the footwear heel by providing projections at the bottom of 75 the cavity in which the pivot penetrates, the upper surface of this pivot being provided with recessed portions with which the projections engage after the rubber heel is placed in position. 80

Other details and advantages will be made clear hereinafter from the description taken in connection with the accompanying drawings which are given merely by way of example. 85

In the drawings,

Figure 1 is a plan view showing a member which is fastened to the heel of the footwear and carrying a pivot for fixing the detachable rubber heel in position. 90

Figure 2 is a section on line 2—2 of Fig. 1.

Figure 3 is a section on line 3—3 of Fig. 1.

Figure 4 is a plan view of a detachable rubber heel showing the recess in which the pivot is adapted to engage. 95

Figure 5 is a section on line 5—5 of Fig. 4.

Figure 6 is a section on line 6—6 of Fig. 4.

Figure 7 is a partial section on the longitudinal axis of an ordinary heel on which a rubber heel is fixed in position. 100

Figure 8 is a partial section on a plane passing through the center of the pivot and making an angle of 90° with the plane of Fig. 7.

Figures 9, 10 and 11 relate to a mode of 105 application of a device according to the present invention to heels of ladies' footwear with round rubber heels, wherein,

Figure 9 is a view similar to Fig. 1 showing the pivot and its support and the means 110 for attaching the said support to the ordinary heel,

Figure 10 is a plan view of a round rubber heel and its recess permitting its engagement with the pivot.

Figure 11 is a central transverse cross-sectional view showing the rubber heel fixed to its support.

Figures 12 to 19 show, in figures corresponding to Figs. 1-8, another mode of carrying the invention into effect, in which 10 the rubber heel carries the pivot which penetrates in a corresponding recess of the member integral with the footwear heel, when placed in position, and wherein,

Figure 12 is a plan view showing the 15 device serving as a support for the rubber heel,

Figure 13 is a section on line 13-13 of Fig. 12,

Figure 14 is a section on line 14-14 of 20 Fig. 12,

Figure 15 is a plan view of a rubber heel showing the pivot which penetrates in the support illustrated in Fig. 12,

Figure 16 is a section on line 16-16 of 25 Fig. 15,

Figure 17 is a section on line 17-17 of Fig. 15,

Figure 18 is a partial section on the longitudinal axis of an ordinary heel on which 30 a rubber heel is held in position, and

Figure 19 is a partial section on a plane passing through the centre of the pivot and making an angle of 90° with the plane of Fig. 18.

35 Figures 20 and 22 are plan views showing the rubber heel in position on the footwear heel prior to rotation through 90° to fix the rubber heel thereto.

Figures 21 and 23 are sections on lines 40 21-21 and 23-23 of Figs. 20 and 22 respectively.

Figs. 1 to 8 relate to a device for attaching a rubber heel, of the same outline as an ordinary footwear heel to the latter.

45 Figs. 1 to 3 show the supporting element for the rubber heel, said support being fixed to the heel of the footwear.

It comprises two parts:-

1. A piece of leather 1 having the same 50 outline as the heel of the footwear and provided with a hole having the shape of a ring surrounding a metal plate hereinafter described. The piece of leather 1 is secured to the heel of the footwear by means of nails 55 or of screws.

2. A plate 2 of nonoxidizable metal composed of two sectors 3 of 90° each, the apices of which face each other. Holes 4 are provided in the sectors to receive screws for 60 the purpose of fixing the plate 2 to the heel of the footwear.

The plate 2 carries at its central part a pivot 6 for a bayonet joint, the upper face 7 of which has two recessed portions 8 in 65 the form of sectors, which are situated above

the corresponding sectors 3 of the plate and are limited by two projections 9. The bottoms of the recessed portions 8 are at the same level as the upper face of the leather piece 1, so that the projections 9 of the pivot 70 project above the latter (Fig. 2).

The lateral faces of the pivot are cylindrical along the recessed portions 8, (Fig. 3), and are inclined or undercut along the projections 9 (Fig. 2) so that at these points 75 the section of the pivot enlarges from the bottom to the top.

The leather ring 1 is provided facing the projections 9, with projections 17 which are bevelled so as to form an undercut edge 80 as clearly illustrated in Fig. 1.

Between the central pivot 6 and the leather piece 1 are provided on the one hand two grooves 33 with lateral cylindrical faces (Fig. 3) on the outside of the recessed portions 8, and two grooves 34 on the outside of the projections 9 (Fig. 2) having a dovetailed section, the larger part of which is situated at the bottom of the heel of the footwear. As can be seen from Fig. 3 the 90 two sectors 3 of the plate 2 form the bottoms of the grooves 33 having lateral cylindrical surfaces.

Figs. 4 to 6 relate to the rubber heel 10. The latter is of the concave-convex type and 95 illustrated in the drawings it has the same outline as the heel on which it is to be fixed.

In the fixing device there is—

1. A ring consisting of four parts 11-11 and 12-12 separated by grooves 13 spaced 100 90° from each other and situated as shown in Fig. 4.

The parts 11-11 are at a higher level than the parts 12-12. The inner and outer faces of the parts 11-11 are bevelled and are such that their larger section is adjacent to the heel of the footwear when the rubber heel is placed in position. The inner and outer faces of the parts 12-12 are cylindrical.

2. At the central part corresponding to the upper part 7 of the pivot 6 there are arranged alternately with 90° sectors 14-14, sectors 15-15, such that the level of the sectors 14-14 corresponding to the elements 11-11 is not so high as that of the sectors 15-15 corresponding to the elements 12-12.

For placing the rubber heel in position the central parts of its ring slide on the pivot 6, when the axis 5-5 (see Fig. 4) makes an angle of 90° with the axis 2-2 (Fig. 1) as illustrated in Figs. 20 and 21. The larger section of the parts 11-11 then cover the circular sectors of the plate while the parts 12-12, the height of which is less, 120 penetrate into the grooves intended to later contain the parts 11-11.

A rotation of 90° of the rubber heel 10 brings the latter into final position and fixes it upon the footwear heel, the parts 11-11 130

of which are dovetailed engaging, due to the resiliency of the substance of which the heel is made, with corresponding grooves at the bottom of the footwear heel (Fig. 7). In order to allow an easy rotation of the rubber heel when fixing the adjacent parts of the recessed portions 8 and projections 9 of the pivot the angles of the tapered projections 17 and the side edges of the elements 11—11 are suitably designed as shown at 16 in Fig. 1 and at 19 in Fig. 4.

Once the rotation is completed and the sectors 15 of the central part of the rubber heel are lodged in the corresponding recessed portions 8—8 of the pivot 6, while the projections 9—9 of the upper part of the said pivot have completely penetrated into the recesses 14 of the central part of the rubber heel, and the ends of the parts 11—11 of the heel have come into contact with the edges 34' of the circular sectors 3, which act as stops, the rubber heel is protected from any angular displacement after it has been placed in position. Due to the parts 12—12 having a lesser height than the parts 11—11, they bear by means of their top 12' upon the sectors 3 of the plate 2 (see Fig. 8) thus preventing all hammering of the rubber against the heel of the footwear. In order to remove the rubber heel from the footwear heel in order to replace it or to interchange it with the rubber heel of the other shoe, so as to compensate the wear according as it is produced, the rubber heel is seized by its sides, and a pull is exerted in such a manner as to raise it uniformly on all points.

Under the effect of the said pull, the parts 11—11 are compressed and leave the bottom 40 of their corresponding grooves while the projections 15 are disengaged from the recessed portions 8—8 of the pivot 6, by moving apart, and the projections 9—9 of the pivot are withdrawn from the recesses 14 of the central part of the rubber heel. As soon as the parts 11—11 are at a level with the upper part of the sectors 3—3 of the plate 2, it is sufficient to impart a movement of rotation through a quarter of a revolution to the rubber heel in order to easily remove it.

Figs. 9 to 11 relate to an application of the above described fixing device to a round rubber heel especially intended for ladies' footwear. The same parts have been designated by the same reference numerals. The parts composing the fixing device and the operation of said device being the same as those above described, it is not therefore necessary to describe them again.

According to this modification the positions of the grooves 33 and 34 such as hereinbefore described are reversed so that the grooves 33, having lateral cylindrical faces 65 along which the introduction of the parts 11

of the rubber heel take place, are provided at the places where the thickness of material of the support 1 is smallest.

The device illustrated in Figs. 12 to 19 is a modification of the above described device. In this arrangement the rubber heel 20 (Figs. 15 to 17) has a pivot 21 similar to the pivot 6 which has been described and the heel of the footwear is provided with a ring 22 having two upstanding parts 23—23 of bevelled section (see Fig. 13) the smaller section of which is situated adjacent to the footwear heel. The parts 23 are interconnected by means of the ring 22 (see Fig. 14) which has section shaped portions as 80 shown in Fig. 12, the apices of which portions face each other. Holes 26 permit the ring 22 to be fixed by means of screws or the like to the heel of the footwear.

The rubber heel 20 is recessed at its central part in order to allow the penetration of the fixing ring 22. At the centre is a pivot 21 having at its upper part two recessed portions and two projections similar to those described for the pivot 6, the projections 27 being arranged opposite grooves 31 which are of dovetail section. Opposite the recessed portions 28 the central recess of the heel has grooves 29 (see Fig. 17) having cylindrical side walls, the bottoms 30 of which are at a slightly higher level than that of the grooves 31 (see Fig. 16) and the side walls of which diverge downwards, one of the walls being formed by the side face of the pivot 21 and the other wall by the tapered projection of the inner face of the groove opposite the projections 27.

When the rubber heel is placed in position (see Figs. 18 and 19), this being effected in the same manner as in the previous case 105 and as illustrated in Figs. 22 and 23, the parts 23 of the ring 22 penetrate into grooves 31 of the rubber heel without their upper surface coming into contact with the bottom of the grooves so as not to harm the 110 flexibility of the rubber heel. The projections 27 penetrate into the pierced recesses 35 existing between the parts 23 and the plates 24, while the recessed portions 28 rest on the said plates, the edges of which act 115 as stops for corners 32 of the rubber heel (see Fig. 17).

It is to be pointed out that the angular displacement of the heel is also prevented by the ends of the parts 23 abutting against 120 the side walls of the grooves 31 when the heel is placed in position.

Moreover the grooves 29 act as air cushions having the plates 24 for lids (see Fig. 19). When walking, the air contained in 125 the said air cushions is compressed and expanded at the same time as the pivot of the rubber heel in such a manner that the said grooves act as shock absorbers while increasing the springiness of the heel.

The fixing device being applied in a permanent manner upon the footwear heel may serve indefinitely; and has the following advantages:—

- 5 1. Interchangeability at will and automatic placing in position of the rubber heel whether the latter have an ordinary or round shape.
- 10 2. One and the same fixing device may serve either for securing a rubber heel of ordinary shape or for a rubber heel of round shape provided that engaging elements of the one are equal and similarly arranged to those of the other.
- 15 3. Instead of comprising two pieces, a leather piece and a metal plate, the fixing device may be moulded in one piece made either of aluminium or of another light and nonoxidizable metal or of a plastic material 20 which is flexible, hardened and relatively light (vulcanite, for instance).
- 25 4. The fixing device may also serve for securing pieces of suitable shape under soles of leather, wood, etc. of the footwear.

25 The rubber heels, also act not only as shock absorbers but also for compensating the abnormal effects resulting from faulty walking.

The rubber heels of round shape and of 30 concave-convex section adapted to the fixing device according to the present invention can, if the greater wear occurs, as actually is the case, on the outer edge of the heel at a point 45° from the longitudinal axis of 35 the shoe, be shifted from the one shoe to the other, and attached, in the case of each shoe in two different positions by rotating it in opposite directions a quarter of a turn. In this manner the normal life of a heel is 40 quadrupled. Also, in addition to their property of acting as shock absorbers, they have a much firmer support than the rotating heels. Moreover they have not the drawback of the latter of being worn on their 45 inner face owing to the continuous friction against the base of the heel of the footwear.

Having now fully described my invention what I claim and desire to secure by Letters Patent is:—

50 1. A detachable resilient heel comprising, a heel member, and a support member attachable to a shoe heel, projections of dovetailed transverse section on the heel member, lateral cylindrical-faced grooves in the support member, other grooves in the support member having a dovetailed transverse section which matches that of the projections, the projections of the heel, when placed in one position on the support member, engaging in the cylindrical-faced grooves thereof, and upon rotation of the heel, engaging in said other grooves.

60 2. A detachable resilient heel comprising, a heel member, and a support member at-

tachable to a shoe heel, projections of dovetailed transverse section on the heel member, lateral cylindrical-faced grooves in the support member, other grooves in the support member having a dovetailed transverse 70 section which matches that of the projections, the projections of the heel, when placed in one position on the support member, engaging in the cylindrical-faced grooves thereof, and upon rotation of the heel, engaging in said other grooves, a central pivot 75 on the support member having lateral undercut faces constituting the inner faces of the said other grooves.

3. A detachable resilient heel comprising, 80 a heel member, and a support member attachable to a shoe heel, projections of dovetailed transverse section on the heel member, lateral cylindrical-faced grooves in the support member, other grooves in the support member having a dovetailed transverse 85 section which matches that of the projections, the projections of the heel, when placed in one position on the support member engaging the cylindrical-faced grooves thereof, and upon rotation of the heel, engaging in said other grooves, a pivot on the support member, recessed portions on the upper part 90 of the pivot limited by projecting portions, a cavity in the heel member, recessed portions in the heel cavity, limited by projecting portions, the support member pivot being received in the heel cavity, and upon the said rotation of the heel on the support member, the projecting and recessed portions of the cavity respectively fitting into the recessed and projecting portion of the support member.

4. A detachable resilient heel comprising, 100 a heel member, and a support member attachable to a shoe heel, projections of dovetailed transverse section on the heel member, lateral cylindrical-faced grooves in the support member, other grooves in the support member having a dovetailed transverse 110 section which matches that of the projections, the projections of the heel, when placed in one position on the support member, engaging in the cylindrical-faced grooves thereof, and upon rotation of the heel, engaging in said other grooves, a pivot on the support member, recessed portions on the upper part of the pivot limited by projecting portions, a cavity in the heel member, recessed portions in the heel cavity limited by projecting portions, the support member pivot being received in the heel cavity, and upon the said rotation of the heel on the support member, the projecting and recessed 120 portions of the cavity respectively fitting into the recessed and projecting portion of the support member, the recessed portions in the pivot being in the form of sectors.

5. A detachable resilient heel comprising, 130 a heel member and a support member, con-

- tacting surfaces on the two members, matching projections and recesses in the surfaces in the form of circular segments, the projections and recesses of one member filling 5 respectively in the recesses and projections of the other member when the heel is in operative position, thus preventing involuntary relative rotary movement between the heel and support members.
- 10 6. A detachable resilient heel comprising, a heel member, and a support member attachable to a shoe heel, projections of dovetailed transverse section on the heel member, lateral cylindrical-faced grooves in the 15 support member, other grooves in the support member having a dovetailed transverse section which matches that of the projections, the projections of the heel, when placed in one position on the support member, engaging 20 in the cylindrical-faced grooves thereof, and upon rotation of the heel, engaging in said other grooves, the projections on the heel member being annular segments of approximately 90°.
- 25 7. A detachable resilient heel comprising, a heel member, and a support member attachable to a shoe heel, projections of dovetailed transverse section on the heel member, lateral cylindrical-faced grooves in the 30 support member, other grooves in the support member having a dovetailed transverse section which matches that of the projections, the projections of the heel, when placed in one position on the support member, engaging 35 in the cylindrical-faced grooves thereof, and upon rotation of the heel, engaging in said other grooves, the projections on the heel member being annular segments of approximately 90°, second projections 40 on the heel member interspaced between the dovetailed projections on the heel member and having a rectangular transverse section of a width equal to the most restricted width of the dovetailed projections, the 45 lateral cylindrical faces and the inclined faces of the dovetailed grooves of the support member alternately corresponding with the faces on the heel projections.
- 50 8. A detachable resilient rubber heel comprising, a heel member and a support member, the heel member having two projections of dovetailed transverse section and two projections of rectangular transverse section, cooperating 55 grooves in the support member for the heel projections, the dovetailed projections being higher than those of rectangular section, recessed portions in the

support member grooves limited by stop shoulders, whereby, when the two members are in operative position, the tops of the 60 dovetailed projections are received in the recessed portions of the support member, and the stop shoulders prevent involuntary relative angular movement of the heel and support members. 65

9. A detachable resilient heel, comprising, a support member, a central pivot on the support member, rectangular section grooves and dovetailed section grooves in the support member, one lateral face of each 70 of which grooves is formed by the pivot, a heel member, projections of rectangular section and projections of dovetailed section, on the heel member, the projections of the heel member when in operative position on 75 the support member, fitting into the grooves of the support member and constituting a bayonet joint connection between the members.

10. A detachable resilient heel, comprising, a support member, a central pivot on the support member, rectangular section grooves and dovetailed section grooves in the support member, one lateral face of each 80 of which grooves is formed by the pivot, a heel member, projections of rectangular section and projections of dovetailed section, on the heel member, the projections of the heel member when in operative position on 85 the support member, fitting into the grooves of the support member and constituting a bayonet joint connection between the members, a cavity in the heel member, between the projections, for receiving the pivot of the support member. 90

11. A detachable resilient heel comprising, a support member, a central pivot on the member, a heel member, two projections on the heel member of rectangular section, two grooves in the support member of rectangular section to furnish a bayonet joint 100 with the projections, sector shaped recesses in the top of the pivot and limited by projections, recessed portions in the heel member and limited by projections, the two members when in assembled position, having the last mentioned heel member projections and recesses respectively cooperating with the last mentioned support member recesses and projections, whereby to hold the members 105 in fixed angular position.

In testimony whereof I affix my signature.

LEOPOLD VAN ROY.
